METHOD OF DEFLOCCULATING BACTERIA

Glenn Green, Lakeville, Ohio, assignor to Syntron
Company, Homer City, Pa., a corporation of
Delaware

Application September 28, 1945, Serial No. 619,233

5 Claims. (Cl. 195—75)

1

This invention relates to a method of treating microscopic organisms, such as bacteria, yeasts, molds and the like, that is particularly applicable to bacterial analysis of water, milk and the like.

Many types of microscopic organisms have clumping or grouping characteristics of growth which are so pronounced in some instances as to be distinguishable on that account. Each such living clump or group of microorganisms when planted or inoculated into a growth media, such as nutrient agar, will produce only one visible colony regardless of the number of individuals which comprise the group. A bacterial analysis, therefore, based on clumps or groups is not accurate because of the possible variation in size of the clumps. Prior methods of bacterial analysis, for example, the standard method of water analysis, involves vigorous shaking of the sample in an effort to disintegrate these clumps, and it is usual to allow for a ten percent error in the analysis.

According to the present invention, I subject microscopic organisms which may be suspended or dispersed in a suitable medium, to high frequency vibration to disintegrate or break up the clumps. Preferably the vibration rate and amplitude are such as not to appreciably destroy the bacteria, where it is desired to promote growth of the bacteria. However, the breaking up of clumps of bacteria may be employed in conjunction with any suitable method of destroying bacteria, in which case precautions against the destruction of some of the bacteria by vibration need not be taken. The breaking up of the clumps of bacteria by vibration may be employed in the preparation of vaccines and in the cultivation of bacteria for various industrial processes, as well as in the examination of water, milk or other substances.

In applying my invention to the analysis of water, I subject water samples to vibration at 3600 to 7200 per minute at an amplitude of about 1/32 inch for about five minutes. If desired, I may add an adjuvant such as a sodium hexametaphosphate in the water sample to facilitate the breaking up of clumps. The cultures then are incubated in any suitable media, such as nutrient agar, for any suitable conditions as to temperature, time, etc.

In the accompanying drawing, forming part of this application, wherein I have shown a preferred form of apparatus for carrying out my method, Figure 1 is a side view partly in section and Figure 2 is an end view partly in section.

Referring to the drawing, there is shown a casing 1 suitably secured within a cabinet 2. At the top of the casing 1 are four vibratory members 11 disposed diagonally across the four corners, each comprising an inverted channel-shaped metal strip 12 with a hole therethrough (not

shown) by which the strip may be bolted or otherwise secured to a top plate 13, and rubber pads 14 have one of their respective faces secured to each side of the channel strip 12 by vulcanization, or in any other suitable manner. The pads 14 are right and left hand, and the faces thereof are substantially parallel. Angle strips 16 are vulcanized to the opposite faces of pads 14 and bolts 17 pass therethrough into a flange (not shown) at the top of casing 1 to secure the vibratory members 11 thereto. Table 13 may be of metal, wood or other suitable material.

The unit for vibrating the table 13 comprises a vibratory motor indicated generally by the numeral 21 and in the preferred embodiment consists of a base 22 of cast steel or other suitable material having a laminated electromagnet 23 secured therein by rivets or in any other suitable manner. The base has holes 24 bored through the ends by which it may be secured to the table 13. The electromagnet 23, which preferably is in the form of a T, is surrounded by a coil or winding 25 which may rest on a cushioning pad 26 of rubber or other suitable material, and a suitable clip 27 holds the coil in place.

The armature 28 is of laminated construction and is substantially in the shape of a C. The laminated plates of the armature are enclosed in thicker side plates 31 on either side, which extend partway along the legs of the C and beyond the armature proper, all the plates being held in assembled position by rivets or in any other suitable manner. Cross bars 29 having suitable bolt holes therein, are positioned between the side plates 31 and are welded or otherwise secured thereto. Adjacent each end of the base are two vibratory members similar to members 11 which are indicated generally by the numerals 32 and 33 and the armature is secured to these vibrator members by bolts 36 passing through the holes in bars 29, and nuts 37 and 38 and spacing washers 39 in between. The spacing washers are interposed between horizontal bars 29 of the armature and the top channel member 40 of the vibratory members (corresponding to channel members 12).

There is thus provided a proper air gap between the armature and the electromagnet in assembled position, and the bolts 36 preferably are adjusted so that their heads 42 are not in contact with the base 22. By reason of the non-magnetic properties of the armature supports 32 and 33 the possibility of the electromagnetic flux being shunted around the air gap into the armature is eliminated. Ordinarily, when the armature is vibrating the amplitude of vibration is such that the heads 42 do not strike the base 22. However, 60 striking surfaces 43 of "Stellite" or other suitable

hard material may be positioned on the base 22 to prevent damage in case accidental impact occurs.

In a compartment or case 45 which preferably is secured to the cabinet 5 housing the apparatus, there is located a rheostat 47 controlled by a knob 48 extending outside of the cabinet. The cabinet also includes a snap switch 49 of the usual type.

The table 13 has posts 51 and 52 at its ends which are firmly bolted to the table by nuts 53 on the ends of the posts, and a cross bar 54 joins the two posts. This bar preferably is made up of an inverted channel 55 and a steel plate 56 welded across the open face of the channel to provide a rigid structure. Nuts 57 and 58 on the ends of posts 51 and 52 adjustably secure the cross bar 54 in position. Recesses 61 are provided in the table and have pads 62 of cork or similar yieldable material on their bottoms to receive the sample jars or bottles 63. These bottles, which may have ground glass stoppers 64, are held firmly in position by hand screws 65 threaded into bar 54 and having rubber or similar resilient pads 66 secured to a plate 67 which is in turn connected to screw 65 by a ball and socket joint 68.

The following specific example will illustrate the carrying out of my method and the operation of the apparatus. Two samples of raw water, by which term I mean water in its condition when it enters the water purification plant, are prepared for microscopic examination or "plating." One sample is first placed in a bottle 63 which is then placed in a recess 62 of the table 13, the stopper 64 applied, and the hand screw 65 turned down until the stopper is held firmly in place. The table and bottle then is set into vibration by supplying electric current to the vibrator, preferably from a 60 cycle source, through the switch 49 and rheostat 47 to the coil 25 to vibrate the table vertically at the rate of 7200 vibrations per minute. The vibration is carried out for five minutes and then both samples are incubated side by side in the same incubator for twenty-four hours. The following table represents the results of a typical series of tests made on raw water, the numbers representing the bacterial count.

Standard Method	Vibrated Sample
200	180
130	390
62	240
210	360
180	340
105	170
110	120
90	120
100	120
115	180
275	340
112	280
Average 141	Average 237
	Percent increase 68

In another series of tests carried out on filtered water, the percent increase on eleven tests was 234% as compared to the standard method of shaking and on disinfected water, that is, water which had received chlorine treatment, the average increase of ten samples was 168%.

Where it is desired to use a lesser frequency of vibration, I may employ any suitable type of rectifier in the circuit with the switch 49, rheostat 47 and coil 25 to give a frequency of vibration of 3600 per minute. The apparatus illustrated is of particular value where a number of samples are

to be vibrated together. I prefer, therefore, to place the sample bottle on a resilient pad 62 of cork, rubber or the like, and hold the sample bottle in place by a resilient pressure applied to the stopper through a pad 66 of rubber or the like, the universal joint 68 allowing the pad to adapt itself to the stopper as required. The base 22 carrying the electromagnet 23 is firmly secured to the table 13 which rests upon the vibratory members 11 on the base 1. The deflocculation of the bacteria may be assisted by the addition of sodium hexametaphosphate, and I prefer to use about one to fifteen parts per million for this purpose, although I do not intend to be limited to these exact proportions.

Various modifications may be made in my invention without departing from the spirit or scope thereof.

I claim:

20 1. The method of deflocculating bacteria for counting which comprises subjecting bacteria suspended or dispersed in a medium to a vertical mechanical vibration of relatively low magnitude and a frequency of 3600 to 7200 vibrations per minute.

25 2. The method of deflocculating bacteria for counting which comprises subjecting the suspended bacteria to a fixed vertical uniform mechanical vibration of relatively low magnitude and at a frequency of 7200 vibrations per minute.

30 3. The method of deflocculating bacteria for counting which comprises subjecting the suspended bacteria to a uniform vertical mechanical vibration of frequency of 7200 vibrations per minute at an amplitude of about $1/32$ inch for about five minutes.

35 4. The method of deflocculating bacteria for counting which consists in subjecting a sample of a liquid containing the bacteria to a fixed vertical uniform mechanical vibration having a frequency of 3600 vibrations per minute and varying the amplitude of the vibrations to provide different degrees of deflocculation.

40 5. The method of deflocculating bacteria for counting which consists in subjecting a sample of the liquid containing the bacteria to a fixed vertical uniform mechanical vibration having a frequency of 3600 vibrations per minute and having a low magnitude for a predetermined period of time, checking the bacteria count of the specimen, reapplying the vibrations to the specimen at an increased magnitude for a predetermined period of time, and again checking the bacteria count of the specimen.
